WINDOW SHADE CONSTRUCTION

Clarence G. Barrows, Hamden, Conn., assignor to
The Safety Car Heating and Lighting Com-
pany, Inc., a corporation of Delaware

Application July 13, 1944, Serial No. 544,721

12 Claims. (Cl. 160—90)

1

This invention relates to window shades. More particularly, it has to do with shades useful, for example, in railway cars and similar places where varying exposures and amounts of sunlight present themselves from time to time and where space limitations must be considered.

It is an object of the invention to provide means wherein translucent and opaque shade materials are combined in a practical and novel manner so that the degree of outside light admitted through a window may be controlled at will. An additional object is the provision of improved roller constructions whereby shades may be moved from the lateral extremities of a window toward the central portion thereof by means of a single crank or operating device. A further object is the provision of a practical shade construction conforming to size and space specifications such that it may be installed in the hermetically sealed space within a double glazed window frame. Still another object is the provision of a universally useful shade construction which may be manufactured and assembled commercially and which has features and advantages not available in the shade constructions heretofore known in the prior art. Other objects and advantages will be in part pointed out as the description proceeds and will in part become apparent therefrom.

The invention accordingly consists in the features of construction, combinations of elements, and arrangements of parts as will be exemplified in the structure to be hereinafter described and the scope of the application of which will be set forth in the appended claims.

In the accompanying drawings, in which only one form of the invention is specifically illustrated:

Figure 1 shows an elevational view of a window frame embodying the invention;

Figure 2 is a sectional side elevation upon an enlarged scale taken along the irregular line 2—2 of Figure 1 in the direction of the arrows;

Figure 3 is a sectional plan view taken along the line 3—3 of Figure 4 in the direction of the arrows;

Figure 4 is a sectional elevational view taken along the line 4—4 of Figure 3 in the direction of the arrows;

Figure 5 is a schematic representation of the novel combination illustrated in Figures 1—4 indicating the mechanical relationship of the parts;

Figure 6 is an elevational view of the window frame illustrated in Figure 1 showing the outer

2

lateral portions of the window opening covered by means of a translucent material;

Figure 7 is a sectional view taken along the line 7—7 of Figure 6;

Figure 8 is an elevational view showing the entire window portion covered by means of the translucent material of the curtain;

Figure 9 is a sectional view taken along the line 9—9 of Figure 8 in the direction of the arrows;

Figure 10 is an elevational view of the window frame showing the central portion covered by means of the translucent material with the two side portions covered by means of an opaque material;

Figure 11 is a sectional view taken along the line 11—11 of Figure 10;

Figure 12 is a further elevational view of the window frame showing the entire window portion covered by means of the opaque material of the shade;

Figure 13 is a sectional view taken along the line 13—13 of Figure 12;

Figure 14 is an enlarged fragmentary elevation showing the connection between the shades and the drawing mechanism therefor; and,

Figure 15 is a section taken along the line 15—15 of Figure 14.

In the embodiment here shown the shade structure is illustrated positioned within the air-tight space formed between double glazing such as might be found in a modern railway car. A roller is positioned extending generally in a vertical direction along each side of the window within a recess of the window frame. And a

crank is provided whereby the leading edge portions of the shades may be unrolled so as to approach one another and meet at the central part of the window. The construction allows an overlapping relationship between the two shades so that novel and useful arrangements of translucent and opaque materials are made possible. Thus, the window may be left unobstructed, or it may be partly or fully screened by the translucent portions, or various relationships of translucent and opaque materials may be combined

so as to let in any amount of sunlight which is available or desired and at the same time prevent direct observation into the interior by anyone on the outside. Also the shades may be made of colored transparent or translucent materials if specific decoration requirements are to be met or if it is desirable to filter the entering light rays in any manner.

In the shade constructions heretofore commonly known and used, one horizontal roller was

usually provided above the window in such fashion that the shade might be pulled downwardly from the top so as to close off a given amount of the window from top to bottom. These structures did not make adequate provision for controlling the amount of light which was to be admitted. Thus, although they could prevent the occurrence of observation from outside into the interior, they gave no choice to the occupants as to the amount of light which would be admitted if privacy was to be secured within. The shade had to be pulled completely to the bottom, thus cutting off all natural light from outside. And correspondingly, no provision was made for modulating the amount of natural light admitted except insofar as it might be wholly excluded from passing through certain portions of the window.

Figure 1 illustrates a window generally indicated at 20 having at its right-hand side a shade portion 22 and at its left-hand side a shade portion 24. A vertically extending draw rod 23 forms the leading edge of shade portion 22 as it is unrolled and similarly a draw rod 25 forms the leading edge of shade portion 24 as it is unrolled. A crank 28 located toward the central upper portion of the frame is provided for controlling the position of the shade portions, as will be described hereinafter. Each roller is so arranged that the first half of the shade to unroll is translucent and the second half opaque. Of course, these portions of the shades may be of any desirable material and color according to specified requirements, their characteristics as specified being illustrative herein.

Figures 6-13 show the manner in which the shade portions may be controlled so as to regulate the amount of light admitted to the interior through the window. In Figure 6 crank 28 has been positioned so as to move translucent portions 22a and 24a over the side areas of the window. Figure 8 illustrates the entire window with portions 22a and 24a cutting off all view through the window but allowing light to pass from the outside through the translucent material of the shade. In Figure 10 the translucent portions have been overlapped somewhat (see also Figure 11) so as to leave a central part where two layers of translucent material are provided. An opaque part on either side is formed by shade portions 22c and 24c. A dividing line between translucent portion 22a and opaque portion 22c is indicated by means of reference character 22b. Likewise the dividing line between translucent portion 24a and opaque portion 24c is indicated by means of reference character 24b. Figure 12 shows each of the shades fully extended (see also Figure 13) so that the opaque portions 22c and 24c completely shield the opening in the window. It is to be observed that the entire operation is performed conveniently by positioning the single crank 28 and that the shades (as well as all mechanism, as will be described) are sealed between the two panes of glass. The driving mechanism itself is screened from view by means of an apron 30. In other words the shades may be of a character to control either the intensity or the character of the entering light rays or both.

Figure 2 illustrates a part of the construction which makes operation of the shade combination possible. The window consists of a channel-shaped casing 40 shown in cross section in Figure 2 which extends around the window and which carries a pane of glass 42 on its outside and a pane of glass 44 on its inside. A sealing gasket 46 is provided between pane 42 and the

casing in combination with a bead 47 to effect an airtight seal around the glass. On the interior side of the window a sealing gasket 48 and a bead 49 are provided between casing 40 and pane 44 so as to form an airtight space insulating the inside from the outside. The shade and its entire operating mechanism, except crank 28, is located within this airtight space.

A shaft 52 is carried within the upper portion 10 of casing 40 between bearings 54 and 55. Shaft 52 is rotatable by means of crank 28, and a sealing sleeve 56 is provided around shaft 52 so as to prevent passage of air into or out of the airtight space between the two panes of glass. The outer end of sleeve 56 is clamped between a flanged portion 54a of bearing 54 and casing 40, the inner or right-hand end of the sleeve, as viewed in Figure 2, being clamped between a nut 57 threaded on shaft 52 and a shoulder 52a formed on the shaft. Sleeve 56 is longer than the distance between bearing flange 54a and shoulder 52a so that it is overlapped therebetween. Sleeve 56 is made preferably of rubber or any other suitable flexible material, and accordingly upon rotation of shaft 52 by operation 20 of crank 28 twists, i. e. its inner end moves relative to its outer end, the overlapping portions of the sleeve accommodating this twisting, while at the same time effectively sealing the air-tight space between the panes of glass against leakage 30 through bearing 54.

Shaft 52 has keyed thereto a crank arm 58 which extends downwardly to form a support for a pinion shaft 60. A pinion gear 62 is carried on the left-hand end of pinion shaft 60, as viewed 35 in Figure 2, and a sprocket 64 is carried on the right-hand end of the pinion shaft. Pinion gear 62 is meshed with an internal gear segment 66 (see also Figure 4) so that rotation of crank 28 and shaft 52 causes relative movement of pinion shaft 60 with respect to internal gear segment 66 so as to effect rotation of pinion shaft 60 and hence of sprocket 64. Sprocket 64 meshes with a sprocket chain 68 which is parallel to arm 58 45 and meshes with a sprocket 70 located upon shaft 52. Sprocket 70 is freely rotatable upon and with respect to shaft 52 and serves by means of an intermediate hub 71 to drive a drive sprocket 72, sprocket 70, hub 71 and sprocket 72 50 preferably being integral. Drive sprocket 72 cooperates with an intermediate sprocket chain 74 (see also Figures 3 and 4) to transmit driving motion to a roller sprocket 76. Roller sprocket 76 drives an integral shade sprocket 78 which in turn meshes with a shade sprocket chain 80 55 (see Figure 3). A pair of sprocket idlers 82 and 83 (see Figure 5) are arranged so as to space the opposite runs of chains 80 and 88a close enough together as to prevent excessive clearance between shades 22 and 24 and hence excessive light leakage therebetween when draw rods 23 and 25 coincide. Sprocket idler 82 is carried by a bracket 84 (see Figure 3) which extends from casing 40. Sprocket idler 83 is similarly mounted at the 60 other side of the frame.

A pair of spindles 88 and 89 on the left and right-hand sides of the frame are connected to shade sprockets 78 and 79, respectively so as to be driven thereby. Spindle 88 extends through 70 a roller 90 which is carried thereupon by means of an end plate 92. Roller 91 at the right-hand side of the frame is similarly carried by means of spindle 89. A web or plug 94 is disposed within roller 90, being freely mounted about spindle 75 88 for movement relative thereto but being pinned

to roller 90 as by a pin 94a. This plug 94 comprises an anchor for the lower end 96a of a spring 96, the upper end of which is attached in any suitable manner to spindle 88. When the roller, web and spring are assembled on spindle 88, spring 96 is put under an initial tension which tends to rotate drum 90 relative to spindle 88. However, as shade 24 is attached to draw rod 25, which is in turn attached to chains 80 and 80a (Figure 5) any relative rotation between spindle 88 and drum 90 has only the effect of tautening shade 24 and does not result in movement of the shade as a whole toward the left, as viewed in Figure 4, so as to wind the shade on the drum. Thus, when spindle 88 is rotated by the operating mechanism in a direction to cause the shade to be wound on drum 90, spring 96 causes the drum to follow the rotation of the spindle and at the same time its tension maintains the shade in a taut condition. Also, when shade 24 is moved to the right, i. e. is unwound from drum 90, by the operating mechanism, spindle 88 is rotated at the same time that draw rod 25 (Figure 5) is drawn in the direction of the arrow. This direction of movement of the parts results in unwinding movement of roller 90, spring 96 forming a driving connection between the spindle and the drum, the tension of the spring, however, remaining substantially constant so as to maintain the shade taut.

Thus in each direction of rotation of spindle 88, spring 96 constitutes the driving connection between the spindle and drum 90, causing the drum to follow the spindle and hence wind or unwind the shade thereon. The present tension in the spring remains substantially constant for either direction of rotation and accordingly maintains the shade smooth as the tendency of the spring is to uncoil regardless of the direction of rotation of the spindle and drum. The spring, however, can only uncoil to the extent of any slack in the shade. A similar arrangement is provided for the roller at the right-hand side of the frame by means of a spring 97. The construction is such that when crank 26 is rotated, a driving force is effected through shaft 52 which is transmitted to the rollers by the sprocket chain system.

Figure 5 shows schematically the entire arrangement and discloses that in the present embodiment sprocket chain 88 is duplicated at the bottom of the window as indicated by 80a. Correspondingly, sprocket idlers 82a and 83a are provided in association with shade sprockets 78a and 79a.

The opposite ends of draw rods 23 and 25 are fixed respectively to sprocket chains 80 and 80a. Draw rod 23 has its upper end attached to the inside of the outer run of upper chain 80 and its lower end similarly attached to the outer run of lower chain 80a (see Figure 5). Draw rod 25 has its upper end attached to the inside of the inner run of upper chain 80 and its lower end similarly fastened to the outer run of lower chain 80a. Thus when the draw rods 23 and 25 are adjacent as shown in Figure 15 there is but little space between them through which light can leak. In order, however, to prevent draw rods 23 and 25 from engaging one another as they advance in the direction of the arrows in Figure 15, and accordingly precluding further movement in these directions, I have provided at each draw rod extremity a guide shoe, such as shoe 100 (Figure 14), provided at its opposite ends with tongues 101 which may be inserted in the chain,

bowing the shoe around the end of the draw rod. Thus, as shown in Figure 15, the bottom ends of draw rods 23 and 25 are each provided with a shoe 100 which, being bowed toward one another, engage as the draw rods approach when moving in the direction of the arrow, thus preventing the draw rods from hitting one another. The upper ends of the draw rods are similarly provided with shoes 100 and hence the rods are guided past one another as the shades 22 and 24 are closed. Thus the shades may be overlapped throughout their entire length, shade 22 being nearer the exterior, and shade 24 being nearer the interior of the structure, as shown in Figure 2, it being this overlapping relationship which makes possible the combination of translucent and opaque colored and uncolored materials.

While I have shown window 20 (Figure 1) so disposed that the shades travel horizontally, it is to be understood that the shades are equally well adapted to operate vertically should such direction of operation be desirable or required. Thus shade 22 and shade 24 may be overlapped throughout their entire length, shade 22 being nearer the exterior and shade 24 being nearer the interior. And it is this overlapping relationship which makes possible the combination of translucent and opaque colored or uncolored materials.

As various modifications may be made of the above invention and as changes may be made in the embodiment herein disclosed, all matter is to be considered as illustrative only and the scope of the application is to be determined solely by the accompanying claims.

I claim:

1. In shade apparatus of the character described, the combination including a pair of shades, means mounting said shades for movement toward one another, and means for moving the leading edge of each shade toward that of the other shade; each shade being divided roughly into two equal portions along a line normal to its path of movement, and one of said portions being formed of an opaque material and the other being formed of a second material through which light rays can pass.

2. The invention of claim 1 wherein the shades are of the roller type and the second portion of each shade is outermost so that it is the first to unroll, and wherein each shade is sufficiently large to cover individually the window with which it is to be used, whereby the second portions of the two shades may be unrolled toward one another and cover the window, and whereby each shade may be extended across the window and the opaque portions cover the window.

3. In a double glazed window of the type having an air space between its panes, the combination with said window including: shade supporting means within said space, a roller shade carried upon said supporting means for movement between said panes, cranking means extending through a side wall of said space for rotating said supporting means, means for moving the leading edge of the shade with respect to said supporting means, and a spring-like, yielding connection between the shade and the rotating means.

4. In a double glazed window of the type having an air space between its panes, the combination with said window including: a shaft-like rod mounted in said space, a roller and roller shade loosely journalled upon said rod, cranking means extending through a side wall of said space for rotating said rod, means within said space for

moving the leading edge of said shade toward and away from said roller, and spring means fastened at one end to said rod and at the other end to said roller to form a yieldable connection between said rod and roller, whereby said shade may be rolled and unrolled with the unrolled portion always remaining under substantially uniform spring tension.

5. The invention of claim 4 wherein said means for rotating said rod includes a sprocket and sprocket chain, and said means for moving the leading edge of said shade includes a connection between said leading edge and said sprocket chain.

6. In a double glazed window of the type having an hermetically sealed air space between its panes, the combination with said window including: a shade movably mounted within said space, mechanism within said space for moving said shade, control means connected with said mechanism and extending through a side wall of said space, and sealing means between said wall and said control means for maintaining the airtight character of said space.

7. In a double glazed window of the type having an air space between its panes, the combination with said window including: a generally vertically extending roller shade mounted within said space, supporting means within said space for said shade at its top and bottom, a rod fastened to the leading edge of said shade and extending thereabove and therebelow, and synchronized driving means including a manually operable crank extending through a said wall of said space for simultaneously applying moving forces to the top and bottom of said rod to move it within said space and toward or away from said roller.

8. In window construction of the character described, the combination with said construction of: a vertically extending shaft-like rod on each side of said window, a roller and roller shade mounted upon each rod, a sprocket mounted upon each rod, and an endless sprocket chain in driving relationship about and between said sprockets, the leading edge of one roller shade being connected to one side of the sprocket chain as it extends between said sprockets, and the leading edge of the other roller shade being connected to the other side of said sprocket chain.

9. In a double-glazed window of the type having an air space between its panes, the combination with said window including a pair of shades

movably mounted within said space, mechanism for moving said shades in opposite directions across said window in parallel lines so that their leading edges may pass one another, the paths of said shades being closely adjacent, and means for facilitating the passage past one another of the leading edges of said shades.

10. Apparatus according to claim 9 wherein each leading edge of each shade is secured to a relatively thick rigid strip, and the facilitating means comprise mutually engageable members associated with said strips to prevent said strips abutting as the leading edges of the shades pass one another.

11. Apparatus as described in claim 10 wherein each of said mutually engageable members comprises a leaf spring which presents a concave resilient surface toward the other and has at each end an attaching tab to hold it in place.

12. Apparatus as described in claim 1 wherein said shades are mounted along the opposite vertical edges of a rectangular window within a sealed space formed by a pair of spaced panes and a window frame construction, and means to operate said shade apparatus including a rotatable shaft mounted in the frame construction and projecting into said sealed space from the exterior thereof.
